ABSTRACT OF THE DISCLOSURE

A UHF tuner device which constitutes an inductance element in cavity resonance. By the employment of inductance coupling selectivity of a tuner device is greatly improved which requires loose coupling for handling signals of narrow fractional band width such as television signals in the UHF band.

BACKGROUND OF THE INVENTION

Field of the invention

This invention relates to a tuner device for use with signals of UHF band, and more particularly to a tuner device which is simple in construction, excellent in frequency selectivity and hence is suitable for use with UHF television signals.

Description of the prior art

In conventional types of UHF tuner devices a conductive casing is partitioned by a conductive partition wall into a plurality of tuning cavities and a relatively large aperture is formed in the conductive partition wall, through which UHF waves are passed to thereby couple the tuning cavities mainly capacitively. However, the capacitive coupling exhibits a low degree of selectivity.

SUMMARY OF INVENTION

The principal object of this invention is to provide a UHF tuner device in which a plurality of cavities are interconnected with one another by inductance coupling to greatly improve selectivity of the tuner device in the UHF band.

Another object of this invention is to provide a UHF tuner device which is designed to make inductance coupling coefficient of cavities variable, by which the inductance coupling coefficient can be set at a desired value after a predetermined tuning is effected, to facilitate manufacturing of the tuner device.

Briefly stated, according to this invention a conductive partition wall is provided in a conductive casing to provide a plurality of cavities such for example as first and second cavities, and a variable capacitor and a conductor connected thereto at one end and functioning as an inductance element are disposed in each cavity, thus constituting first and second variable tuners. Then, the other ends of the conductors are connected to the partition wall and the partition wall is cut off near the portion surrounding the connecting point of the conductors to form a slit, thus ensuring that the partition wall between the conductive casing and the connecting point of the conductors and the partition wall performs the function of a coupling inductance element between the first and second variable tuners. Accordingly, this invention is suitable for use in the tuner device of UHF television receivers.

Other objects, features and advantages of this invention will become apparent from the following description taken in conjunction with the accompanying drawings, in which:

BRIEF DESCRIPTION OF DRAWINGS

FIG. 1 is a top plan view, partly in cross-section, illustrating one example of a tuner device of this invention;

5 FIG. 2 is a cross-sectional view taken along the line A—A in FIG. 1;

FIG. 3 is a cross-sectional view taken along the line B—B in FIG. 1;

FIGS. 4 to 6, inclusive, are cross-sectional views, similar 10 to FIG. 1, illustrating modified forms of the principal part of this invention;

FIG. 7 is an equivalent circuit of the example shown 15 in FIG. 3; and

FIGS. 8 and 9 are equivalent circuits of the example depicted in FIG. 6.

DESCRIPTION OF THE PREFERRED EMBODIMENTS

The following will describe one example of the tuner 20 device of this invention with reference to the drawings.

Reference numeral 1 indicates a casing of the tuner device, which consists of top, bottom, front, rear, left and right side plates 1a, 1b, 1c, 1d, 1e and 1f made of a conductive material. In parallel with the front plate 1c and the rear plate 1d a partition wall 2 made of a conductive material is provided in the casing 1, dividing it into two and providing first and second cavities 3a and 3b. Rod-like central conductors 4a and 4b, each constituting an inductance element, are disposed centrally of the cavities 3a and 3b in parallel with the top and bottom plate 1a and 1b and the partition wall 2. Meanwhile, a rotary shaft 5 extends between the front plate 1c and the rear plate 1d and is journaled therein adjacent the left side plate 1e. The rotary shaft 5 extends outwardly of the front plate 1c.

30 Affixed to the rotary shaft 5 in the respective cavities are rotary discs 7a and 7b constituting respective elements of variable capacitors 6a and 6b. Fixed plates 8a and 8b of the variable capacitors 6a and 6b are secured respectively to insulators 9a and 9b attached to the bottom plate 1b.

40 Each one end of the central conductors 4a and 4b is coupled respectively to the fixed plates 8a and 8b of the variable capacitors 6a and 6b. The central conductor 4a and the variable capacitor 6a constitute a first tuner 10a, while the central conductor 4b and the variable capacitor 6b constitute a second tuner 10b. The tuning frequency of each tuner substantially depends upon the inductance value of its central conductor and the capacitance value of its variable capacitor. Further, the rear plate 1d and the front plate 1c have centrally disposed apertures 11a and 11b respectively, through which, for instance, an input lead wire 12a and an output lead wire 12b are inserted into the casing 1 and hence are bent, as depicted, to form loops 13a and 13b coupled to the central conductors 4a and 4b respectively, while the respective free ends of the wires 50 being connected to the interior of the rear plate 1d and the front plate 1c.

55 In this invention the central conductors 4a and 4b are bent in the form of an L and their ends to be grounded are connected to the partition wall 2 at opposing points 14a and 14b adjacent, for example, the right side plate 1f, causing the partition wall portion 2a (in FIG. 3) between the connecting points 14a, 14b and the casing 1 to function as a coupling inductance element. For this purpose, a

60 narrow slit or aperture 15 is provided between the partition wall portion 2a and the casing 1. The slit or aperture 15 is selected to be small in area and is not of the type through which the two tuners 10a and 10b produce capacitive coupling as in the prior art tuner device of this kind. That is, the aperture 15 serves to cause the partition wall portion 2a between the connecting points 14a, 14b and the casing 1 to present an inductance with respect to a working frequency of, for instance, the UHF band. In the ex-

65 70 75 80 85 90 95

ample illustrated in FIG. 3, a narrow slit is formed in the partition wall adjacent the right side of the casing 1 in the form of a "C," providing the partition wall portion 2a in spaced relation to the partition wall 2, and the connecting points 14a and 14b are located on the left marginal edge of the partition wall portion 2a. However, the slit may be formed in a manner so that the partition wall portion 2a and the partition wall 2 are contiguous to each other as in examples described later on.

It is desired in practice to adjust the inductance of the partition wall portion 2a. To this end, an additional slit 2b is formed which is contiguous to the slit 15 and a conductive plate 20 covering the slit 2b is designed to be slidably moved on the partition wall portion 2a. In order to move the conductive plate 20 from the outside of the casing 1, one end of a rod 21 is secured to the conductive plate 20 and its free end is projected outside of the casing 1 through an aperture 22 bored in the wall of the casing 1. By moving the conductive plate 20 with such a rod 21, the area of the partition wall 2a is changed at will so as to adjust the inductance coupling coefficient of the partition wall portion 2a. After a predetermined adjustment of the inductance coupling coefficient of the partition wall portion 2a the rod 21 is fixed to the casing 1 by means of soldering or other adhesives as indicated at 23, thus maintaining the inductance coupling at a predetermined value. This remarkably facilitates manufacturing of the tuner devices, since adjustment of the inductance coupling coefficient can be effected easily and rapidly without necessity of precisely constructing the partition wall portion 2a of such an area and shape as predetermined from the very beginning of the manufacturing operations.

FIG. 4 illustrates a modified form of the principal part depicted in FIG. 3, in which the connecting points 14a and 14b are located on both the partition wall 2 and the partition wall portion 2a across the slit.

In FIG. 5 there is illustrated another modification of the principal part of the tuner device, in which the partition wall 2 and the partition wall portion 2a are almost continuous to each other and narrow slits 15a and 15b are respectively provided in the partition wall portion 2a along the portions adjoining the top and bottom plates 1a and 1b of the casing 1, as illustrated in the figures. That is, the upper and lower marginal portions of the partition wall 2 are slightly cut off a length corresponding to the sum of $(d_1 + d_0 + d_2)$, d_1 being the distance on the side of the left side plate 1e from the connecting point 14a or 14b, d_0 the thickness of the central conductors 4a and 4b and d_2 the distance on the side of the right side plate 1f from the connecting point 14a or 14b.

In such a case the connecting points 14a and 14b are not at zero potential or the potential of the casing 1, and the portion 2a of the partition wall 2 having formed therein slits 15a and 15b functions as an inductance element and consequently the central conductors 4a and 4b are connected to the casing 1 through an inductance element 1₁ between the connecting point 14a or 14b to the bottom plate 1b or an inductance element 1₂ between the connecting point 14a or 14b to the right side plate 1f. As a result of this, the tuner device described above becomes equivalent to a circuit such as shown in FIG. 7, which consists of a parallel tuning circuit 10a of an inductance element L₁ of the central conductor 4a and a variable capacitance element C₁ of the variable capacitor 6a, another parallel tuning circuit 10b of an inductance element L₂ of the central conductor 4b and a variable capacitance element C₂ of the variable capacitor 6b and a parallel connection of the inductance elements 1₁ and 1₂ which is inserted between the connection point 16 of the inductance elements L₁ and L₂ and the connection point 17 of the variable capacitance elements C₁ and C₂. Thus, the tuning circuits 10a and 10b are coupled with each other through the inductance elements 1₁ and 1₂. In order to set the coupling between the tuning cir-

cuits 10a and 10b at a predetermined value, it is sufficient to select suitably the inductance values of the inductance elements 1₁ and 1₂. The inductance values of the inductance elements 1₁ and 1₂ depend upon the characteristic impedance of the portion 2a having formed therein the slits 15a and 15b and the distances d_1 and d_2 . In our experiment in which the thickness d_0 and the width d_0' of the central conductors 4a and 4b are selected to be 0.5 mm. and 1.5 mm. and the partition wall 2 is cut off 1 mm. wide and 7 mm. long at the upper and lower marginal edges and $d_1 = d_2 = 3.5$ mm., coupling in the band of 15 mc. could be obtained at 600 mc. Further, the provision of the conductor covering the slits 15a and 15b such as above described with FIG. 3, enables the area or shape of the partition wall portion 2a to be changed suitably, so that the inductance values of the inductance elements 1₁ and 1₂ can be made variable in the circuit depicted in FIG. 7. In the example shown in FIG. 5 or those in FIGS. 3 and 4, the two cavities 3a and 3b are interconnected through the slits 15a and 15b, but the slits 15a and 15b are very small in area and hence their functioning as coupling windows can be neglected.

FIG. 6 illustrates another embodiment of this invention, in which the slits 15a and 15b are formed in the partition wall 2, the length of each slit corresponding to the sum of the distances d_1 and d_2 on one side and the other side of the connecting points 14a and 14b of the central conductors 4a and 4b. Also in this example, the connecting points 14a and 14b of the central conductors 4a and 4b are not at zero potential or at the potential of the casing 1 as in the foregoing example and the portion of the partition wall 2 having formed therein the slits 15a and 15b performs the function of an inductance element. Namely, the free ends of the central conductors 4a and 4b are connected to the casing 1 through the inductance elements 1₁ and 1₂ corresponding to the distance d_1 and d_2 on the partition wall 2 and hence grounded. Accordingly, the above-described tuner device is electrically equivalent to a circuit such as shown in FIG. 8 which consists of a parallel circuit 10a of an inductance L₁ of the central conductor 4a and a capacitance C₁ of the capacitor 6a, another parallel circuit 10b of an inductance L₂ of the central conductor 4b and a capacitance C₂ of the capacitor 6b and a parallel connection of the inductance elements 1₁ and 1₂. The inductances L₁ and L₂ are connected to each other and the capacitances C₁ and C₂ are also connected to each other, while the parallel connection of the inductance elements 1₁ and 1₂ being connected between the connecting point 16 of the inductance elements L₁ and L₂ and the connecting point 17 of the capacitances C₁ and C₂. Thus, the both tuning circuits 10a and 10b are interconnected through the inductance elements 1₁ and 1₂. In order to change the coupling degree of the tuning circuits 10a and 10b as desired, it is sufficient to design the circuit shown in FIG. 8 such that the inductance value of the inductance element 1₁ or 1₂ can be changed at will.

For this purpose, a slit 15c is formed in the inductance element 1₁ or 1₂ substantially vertically to the current path therethrough as shown in FIG. 3. This causes an increase in the impedance of the portion of the partition wall portion corresponding to the distance d_1 . By suitably covering the slit 15c with a conductive member 20, the circuit becomes equivalent to that depicted in FIG. 8 in which the inductance element 1₁ or 1₂ has been made variable, and consequently the circuit is equivalent to that shown in FIG. 9. That is, the impedance or the inductance of the portion of the partition wall portion corresponding to the distance d_1 is varied to a desired value to change the coupling degree of the circuits 10a and 10b, and therefore adjustment of the bandwidth can be accomplished. Further, fine adjustment of the inductance can readily be effected by the employment of a screw as the conductive member 20.

Reference character *k* in FIGS. 7 to 9 indicates the coupling coefficient between the inductances L_1 and L_2 .

In accordance with this invention, one portion of the partition wall 2 between the variable tuners 10a and 10b is utilized as a coupling inductance element and the variable tuners 10a and 10b are coupled through the coupling inductance element, as has been described in the foregoing. Further, since one portion of the partition wall 2 is used as the coupling inductance element, coupling of the variable tuners 10a and 10b can be made extremely loose. Therefore, this invention is suitable for use in a tuner device which is employed in the case where the fractional band width is narrow as in the television signals of the UHF band and loose coupling is required.

It will be apparent that many modifications and variations may be effected without departing from the scope of the novel concepts of this invention.

What we claim is:

1. In a tuner device having a conductive casing, a partition wall electrically connected to said conductive casing for partitioning said conductive casing into a plurality of cavities, and a plurality of variable capacitance elements, one said element located in each of said plurality of cavities, said conductive casing and said partition wall being grounded, the improvement comprising:

said partition wall having means forming a pair of slits therein located along opposite marginal edges of said partition wall at one end portion thereof

for providing electrical potential with respect to the ground level at said one end portion, and a conductor extending parallel to said slits and having one end thereof connected to each of said plurality of variable capacitance elements and an opposite end thereof connected to said partition wall at said one end portion where said partition wall has electrical potential with respect to the ground level, whereby inductive coupling is effectively obtained between adjacent cavities.

2. A tuner device as claimed in claim 1 further characterized by another slit formed contiguous to one of said pair of slits and approximately at right angles thereto, and a conductive plate slidably covering said contiguously formed slit to change the effective area of said one end portion of said partition wall.
